UNITED STATES PATENT OFFICE.

WILLIAM GEORGE BEATTY, OF FERGUS, ONTARIO, CANADA.

EXTENSION-LADDER.

1,170,395.

Specification of Letters Patent. Patented Feb. 1, 1916.

Application filed October 9, 1912, Serial No. 724,775. Renewed December 23, 1915. Serial No. 88,460.

To all whom it may concern:

Be it known that I, WILLIAM GEORGE BEATTY, of the town of Fergus, in the county of Wellington, in the Province of Ontario, Dominion of Canada, have invented 5 certain new and useful Improvements in Extension-Ladders; and I hereby declare that the following is a full, clear, and exact description of the same.

10 My invention relates to that class of extension ladders in which the extension units are provided with locking members to engage the rungs of the units below them for the purpose of holding the extension units 15 in their elevated positions. Heretofore these locking members have been pivoted to the risers of the extension units near their lower ends, so as to swing by gravity into operative relation with the rungs of the ladder 20 units below them, and in the lowering of the extension units, these locking members owing to their gravitational character, swung into engagement with the rungs as the extension unit descended, and caused the user to manually 25 release the locking members therefrom.

The object of my present invention is to provide these locking members with gravity 30 latches projecting into the path of the rungs as the extension unit descends and moved by said rungs to close the rung-entrances to the gripping elements of said locking members during such descent, and dropping into an inoperative position to open said 35 entrances when the extension unit rises.

For an understanding of the invention, reference is to be had to the following description and to the accompanying drawings, in which;

40 Figure 1, is a front elevation showing the use of the invention; Fig. 2, is a section of the line $a-a$ Fig. 1, showing the locking member engaging with a ladder rung, and the pivoted latch in an inoperative position; 45 Fig. 3, is a similar view to Fig. 2, showing the position of the locking member and pivoted latch when the extension unit is being raised; Fig. 4, is a similar view to Figs. 2 and 3, showing the position of the locking member and pivoted latch when the extension unit is being lowered; Fig. 5, is a front elevation of the casing for the locking member; Fig. 6, is a side elevation of the construction shown in Fig. 5; Fig. 7, is 50 a section showing the locking member and

riser; Fig. 8, is an edge elevation of the construction shown in Fig. 7.

Like characters of reference refer to like parts throughout the specification and drawings.

60 The extension unit consists of a set of risers a and a plural number of rungs b, b' . Pivoted to the inner face of each riser a near the lower end thereof, is a locking member c . As shown in Fig. 7, this locking member c consists of a substantially triangular-shaped casting with a pivot hole d at its upper end, for the pivot e to pivotally connect it to the riser. The body of the locking member c is apertured as shown at f and g , 65 for the purpose hereinafter described.

At the lower left-hand corner of the locking member c is a substantially U-shaped gripping element h to engage with the rungs i of the ladder unit j , the right side of the 70 gripping element h being elongated as shown at h' and formed with an angular extension h'' having a downward inclination to the right for the purpose hereinafter described.

80 Pivoted to the side h' of the gripping element is a latch k of a length slightly greater than the distance across the entrance l of the gripping element.

Partly covering the locking member c is 85 a case o , having at its top end an inwardly arranged offset p , and near its lower end a boss q , the inner face of which is in the same plane as that of the offset p . The offset p and the boss q are employed as spacers to 90 separate the case o from the adjacent side of the riser a a distance equal at least to the thickness of the locking member c , so that the locking member can swing freely between the riser and the case o .

95 When the locking member c and the case o are secured to the riser a , the boss q extends through the aperture f in the locking member c , and is so positioned therein that the locking member does not come into contact 100 therewith during its swinging movements.

The case o is bolted to the riser by the bolts e, e', e'' and it is from the bolt e that the locking member swings into its operative and inoperative positions. In the bottom of the 105 case o is a rung aperture r through which passes the rung b , the aperture g being provided in the locking member c for the movement of said locking member without impedance by the rung b .

110

In the use of the invention the locking members *c* and casings *o* are secured to the inner faces of the risers near their lower ends as above described, and when the ladder units are in an inclined position, which is their normal position when set up, the locking members *c* swing to the left from the pivot bolts *e* and bring the gripping elements *h* into position to engage the rungs *i*.

10 When the extension unit is moving upward, as shown in Fig. 3, the latch *k* assumes the position shown in that figure and in Fig. 7, and leaves the entrances *l* to the gripping elements *h*, open so that when the gripping elements are raised slightly above the rung *i*, and then lowered into the position shown in Fig. 2, the rung *i* will enter the gripping element and be engaged thereby and the locking members will then hold 15 the extension unit in its elevated position.

15 To lower the extension unit, the latter is raised until the gripping elements *h* are slightly above the ladder rung *i*, and then the locking members are moved to the right 20 until they are entirely free of the rung *i*. The extension unit is then lowered, as shown in Fig. 3, and as it descends, the rungs below it successively engage the angular extensions *h* which automatically move the locking 25 members to the right, and thus prevent the rungs *i* getting behind them to impede the lowering movement of the extension unit. The latches *k*, then coming into engagement 30 with the successive rungs as shown in Fig. 4, are moved by them to close the entrances *l* to the gripping elements and prevent them engaging any of the lower rungs during the 35 lowering movement of the extension unit, the latches *k* as they pass each rung automatically opening by gravity into the position 40 shown in Figs. 3 and 7. In this way,

the extension units can be lowered to their full length without any possibility of the gripping elements engaging with any of the lower rungs during the lowering movement 45 of the extension units.

If it is desired to lower the extension unit from any elevated position to any other elevated position on a lower plane, the *modus operandi* described is carried out until the 50 locking members *c* have descended below the desired rung. The extension unit is then raised until the gripping elements *h* are slightly above said rung, when the locking members *c* will automatically swing by gravity 55 to the left and then when the extension unit is lowered the gripping elements will engage it, the latches *k* during this upward movement of the extension unit remaining in the position shown in Figs. 3 and 7. 60

Having thus fully described the nature of my invention, what I claim as new and desire to secure by Letters Patent, is:—

In an extension ladder, a locking element so pivoted to an extension ladder section as 65 to tend to swing toward an adjoining ladder section and having at its lower end a substantially U-shaped rung-gripping member, one side of which is elongated and is provided with an angular extension having a 70 downward inclination from the entrance to the rung-gripping member to engage the ladder rungs and move the locking element to the proper side thereof for the unimpeded descent of the extension section, and a latch 75 pivoted to said angular extension to close the entrance to the rung-gripping member.

Fergus, September 21st, 1912.

WILLIAM GEORGE BEATTY.

Signed in the presence of—

A. C. DEACON,
R. D. KERR.
